UNITED STATES PATENT OFFICE.

STANISLAS S. PICARD, OF PROVIDENCE, RHODE ISLAND.

CARRIER FOR BRAIDING-MACHINES.

1,337,155.

Specification of Letters Patent. Patented Apr. 13, 1920.

Application filed October 27, 1919. Serial No. 333,495.

To all whom it may concern:

Be it known that I, STANISLAS S. PICARD, a citizen of the United States, residing at Providence, in the county of Providence and State of Rhode Island, have invented new and useful Improvements in Carriers for Braiding-Machines, of which the following is a specification.

This invention relates to certain new and useful improvements in a carrier for braiding machines, and it has for its primary object to provide an improved carrier which will guide and direct itself from one channel or guideway to the following one in a very efficient and practical as well as proper manner.

The invention consists broadly in the provision of a two part carrier with one part arranged slightly in advance of the other and yieldably related thereto whereby the lower or rear part may have a longer bearing in the present guide or channel while the forward part is entering the adjacent guide under the direction and control of the rear part.

In the drawing:

Figure 1 is a side elevation of the improved carrier;

Fig. 2 is an end elevation thereof; and Fig. 3 is a horizontal section therethrough on line 3—3 of Fig. 1, depicting the yieldable or resilient connection between the parts of the carrier.

Referring more in detail to the drawing, the numeral 1 designates the lower part of the carrier of a braiding machine, and 2 the upper part which is pivotally connected by means of a vertically disposed pivot screw 3 passed upwardly through the bottom part and threaded in the top part whereby the one may have pivotal movement relative to the other. Each part is shaped alike so as to readily follow in the guideways, which are usually a series of communicating or intersecting circles, and the top part is superposed on the bottom part in a slightly advanced relation whereby its nose or front end will enter the adjacent guideway prior to the rear end of the bottom part leaving the present guideway. By this operation the proper channel or guideway will always be selected or entered.

The parts of the carrier are formed in their opposing or bearing faces 4 with sub-

stantially semi-cylindrical recesses 5 supplementing one another in the formation of spring chambers, one being in advance of the pivot 3 and the other to the rear thereof. In each spring chamber is compressed a coiled spring 7 bearing in opposite directions on the end walls of the four recesses 5. Their function is to normally hold the top and bottom parts in operative alignment, permitting them to relatively yield as the upper part enters the adjacent guideway ahead of the supporting lower part.

The bobbin-carrying portion 8 is secured to the stubshaft 9 which is fixed to and carried by the top part, as is clearly depicted in Figs. 1 and 2.

In operation, as the carrier passes over from one circular guideway to the next so as to bring the thread of the carrier either inside or outside, depending upon the traverse of the carrier which is to the left as viewed in the drawing, the bottom part, by reason of its rearward projection will still be guided in the present guideway while the top part has left it and is entering the next guideway. By reason of the resilient connection between the parts the top part will be directed into the proper succeeding guideway in an accurate manner.

Having thus described my invention, what I claim as new and desire to secure by Letters Patent is:

1. A carrier for braiding machines, comprising a bottom supporting part, a top bobbin-carrying part superposed thereon in slightly forwardly offset relation so as to lead the bottom part, both parts shaped to operate in the guideways of a braiding machine, a pivot pin disposed vertically and pivotally connecting the parts, the bearing faces of the latter being formed with component chamber-forming recesses, and coiled springs disposed in the chambers formed by the recesses for resiliently holding the parts in proper relation.

2. A carrier for braiding machines, comprising an upper and a lower part connected for swinging about a vertical pivot, one part being disposed in advance of the other, and means resiliently holding the parts relatively operative.

3. A carrier for braiding machines, comprising resiliently connected parts arranged one in advance of the other and each formed to be received in the guideways.

100

105

110

4. A carrier for braiding machines, comprising yieldably connected superposed parts, and each formed to be received and travel in the guideways and one set forwardly of the other, the upper part carrying the bobbin.
5. A carrier for braiding machines, comprising pivotally connected, relatively superposed parts each formed to be received and adapted to travel in the guideways of a braiding machine.
- 10 6. A carrier for braiding machines, comprising a pair of superposed parts arranged one slightly in advance of the other, and each formed to be received and travel in the guideways and means yieldably connecting
- 15

the parts for holding them operatively related.

7. A carrier for braiding machines, including relatively movable parts each formed to travel in the guideways, said parts being arranged so that an end of each projects outwardly beyond the adjacent end of the other, and a bobbin support carried by one of the parts.

25 In testimony whereof I have signed my name to this specification in the presence of two subscribing witnesses.

STANISLAS S. PICARD.
